CONTAINER

Nelson Geertsen, Chicago, Ill., assignor to American Can Company, New York, N. Y., a corporation of New Jersey

Application December 31, 1940, Serial No. 372,665

2 Claims. (Cl. 220—54)

This invention relates to sheet metal cans or containers of the character having removable tearing strips and has particular reference to the provision of a notched area on the slit end of the body which eliminates sharp corners on a separated cover which results from the severance of the tearing strip.

In tearing strip containers of usual construction the removal of the tearing strip opens the container and also produces a cover which is thereafter utilized as a reclosure. Such a reclosure frequently is adapted to set upon a collar of the container. Sometimes the collar is a separate member which is secured in the container body and sometimes such collar is formed as an integral part of the body.

In either case the collar furnishes a smooth top edge on an opened container and backs up the usual bottom score line cut in the container body which sets off the tearing strip. The top score line if not properly made or located particularly in the side seam region will upon removal of the tearing strip leave a jagged raw edge or sharp corner on the cover after it is separated from the container. Such a sharp corner constitutes a cutting hazard to the hands of the user.

In order to avoid having sharp edges on a separated cover of the usual type, it is necessary to very accurately register the end slit in relation to the upper score line during manufacture of the container bodies, or to space the slit well above the score line and in either event this often proves unsatisfactory.

The present invention contemplates overcoming this difficulty by preparing the body shank with a cut out notch on the slit end of the body which entirely removes a small amount of the metal both above and below the upper score line at the lap section of the side seam without weakening the can and this eliminates any sharp corners that might otherwise remain after separation of the cover, thus insuring a no-cut feature.

An object of the invention is the provision of a can having an internal collar band and a tearing strip provided in the body wall which when removed produces a separate cover closure for the can, the continuous severed edge of which is free of narrow projections or sharp corners.

Another object of the invention is the provision, in such a can, of a body which is prepared with a wide cut-out notch on the slit end of the container body blank which straddles the top score line of the tearing strip so that upon removal of

the tearing strip, a continuous severed edge portion remains along its top edge which forms the edge of a slip cover reclosure.

Numerous other objects and advantages of the invention will be apparent as it is better understood from the following description, which, taken in connection with the accompanying drawing, discloses a preferred embodiment thereof.

Referring to the drawing:

Figure 1 is a front elevational view of the upper portion of a container embodying the invention, with parts broken away and parts shown in section;

Fig. 2 is an enlarged detail perspective view of complementary portions of the tubular container body showing notched and bent side seam portions as they appear from the outside and just prior to being joined;

Fig. 3 is a view of the interlocked fragments shown in Fig. 2 as viewed from the inside of the container and showing a notched out area straddling the top score line; and

Fig. 4 is an enlarged detail view of portions of a substantially flat body blank showing the notch cut into one edge of the body where it extends across the top score line before the body is brought into final form.

As a preferred embodiment of the invention there is shown in the drawing a sheet metal collar can of the tearing strip variety comprising a cylindrical container body 11 (Fig. 1) having its longitudinal edges joined in a side seam 12 and having top and bottom ends secured to the body and showing such a top end 13 secured in place by a suitable end seam 14.

In accordance with the instant invention the body blank 11 is cut as best illustrated in Fig. 4 of the drawing. The right hand end of the blank is slit as at 15 and 16 for the purpose of providing lap and hook sections along this edge of the blank. A cut-out notched section 17 is located intermediate the slits 15 and 16 so that it straddles an upper score line 18. A lower or similar score line 19 is located below and is spaced parallel from the score line 18 to provide a tearing strip 22 for opening a finished container. At the opposite edge of the blank a tearing tongue 23 constitutes a continuation of the tearing strip 22. This cutting or tearing section may also include the notches 24, 25 which extend into the terminal ends of the score lines 18 and 19.

The upper corner of the blank, at the left in Fig. 4, is cut along a diagonal line as at 26 in the usual manner to reduce the area at the lapped edge so as to facilitate the flanging operation in

the manufacture of the container. Other notched-out sections 27, 28 on the tongue end of the blank produces the usual short lap sections at the side seam joint and also set apart extending sections 29 and 32, which upon bending, form the outer hook sections of the container body (Fig. 2).

Fig. 2 of the drawing illustrates fragments of a container body blank after it has been rolled into tubular form but prior to having the seam edges joined together. This view shows a short hook section 33 set off by the slit 15 and the notch 17 and which is arranged to be interlocked with the hook section 29 on the opposite end of the blank. The slit 15 also separates the hook section 33 from an adjacent short inner lap section 34. The slit 16 (Fig. 4) separates a lap section 35 and a hook section 36.

Fig. 3 of the drawing shows the inner fragments of the container body blank illustrated in Fig. 2, joined together in a lock and lap side seam joint. This view illustrates the lap sections 34 and 35 resting against the outer lap sections of the can body. The hook parts 29 and 33 give an additional lock seam section 37 which together with the major lock seam section, indicated at 38 and formed by interlocking the hook sections 32 and 36, produce a container of increased strength.

The straddled notch section 17 forms a short lap section at 39 (Fig. 3) and results in a reduced area at the lap. Aside from the advantages heretofore described, it also effects a substantial saving in the quantity of solder required in securing the blank seam edges together in forming the side seam joint 12. Following the usual soldering operation the open ends of the cylindrical body are flanged in the usual manner.

The seam soldered, flanged body is now in condition to receive its collar band 42. Such a band is here shown as being of the continuous type and as having been inserted in the upper end of the body. Both collar band and body wall are beaded outwardly as at 43 to secure the collar in its fixed position. Such a collar is preferably formed with an inwardly curled edge as at 44 which furnishes a smooth mouth for the opened container.

A usual form of bottom can end may then be secured to the lower opened flanged end of the can body by an end seam joint similar to the top end seam (Fig. 1) after which the container may be filled, closed and sealed by the top end member 13 in the end seam joint 14.

Removal of the tearing strip 22 in the usual manner as by a key produces a separated reclosure of the slip cover type which includes all of the severed body wall above the top score line 18 which is secured to the top end 13. Such a severed body wall has a continuous edge determined by the lower score line 19.

The inner margin of the notch 17 (Fig. 3) forms

a straight edge as at 45 on the inside of the body and this terminates the tearing strip 22 along the score line 18 so that there will not be any jagged or feather edge left on the can. This

form of construction provides a slip cover reclosure which is free of narrow hanging projections or extending sharp corners that often result from removal of the tearing strip in containers that do not possess this no-cut feature.

10 It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

20 1. A sheet metal container comprising a tubular body having a side seam, and a top end member secured to said body, said body having a removable tearing strip formed in the body wall adjacent said end, one end of said tearing strip terminating at said side seam, said strip having its opposite end projecting beyond the seam to constitute a tongue, said tearing strip being set off by substantially parallel upper and lower score lines along which the tearing strip is separated from said body during removal for disconnecting the end member in opening the container, the body wall at said side seam being cut away to provide a notch extending on opposite sides of the upper of said score lines and spaced above the lower of said score lines at the end thereof opposite from said tearing strip tongue to terminate said upper score line inwardly of the side seam, whereby breaking of the score line by removal of said tearing strip leaves a substantially smooth metal edge on the removed end member.

25 2. A sheet metal container comprising a tubular body including a side seam and a collar band, a top end member secured to said body, said body 30 having a removable tearing strip disposed adjacent said collar band set off by upper and lower spaced score lines severable from the body wall to provide a slip cover reclosure member, said reclosure member utilizing said collar band as a friction seat when in reclosing position, the material of the body in the region of the tearing strip being provided with an inwardly disposed notch 35 extending on opposite sides of the upper of said score lines at the terminus of the tearing strip 40 on the inner lap section of the side seam to terminate said score line inwardly of the side seam, said notch being spaced above the lower of said score lines, whereby to provide a substantially smooth metal edge on the reclosure member after said tearing strip has been removed.

NELSON GEERTSEN.
